UNITED STATES PATENT OFFICE.

MARTIN J. KELLY, OF NEW BRITAIN, CONNECTICUT.

WATER-CLOSET-CONTROLLING DEVICE.

1,123,550.

Specification of Letters Patent.

Patented Jan. 5, 1915.

Application filed March 28, 1914. Serial No. 827,953.

To all whom it may concern:

Be it known that I, MARTIN J. KELLY, a citizen of the United States, residing at New Britain, in the county of Hartford and State of Connecticut, have invented certain new and useful Improvements in Water-Closet-Controlling Devices, of which the following is a specification.

My invention relates to improvements in water closet controlling devices and the object of my improvement is to provide in combination with a water closet seat and water supply tank therefore means for shutting off the water and for permitting the tank to discharge the water therein, and effecting the usual flushing while being so discharged, immediately upon release of the seat after use and for closing the discharge outlet of the tank and turning on the water so as to permit the tank to fill, subject to the control of the usual controlling devices provided in the tank when the seat is again brought into use.

In the accompanying drawing: Figure 1 is a perspective view of a water closet seat and water tank equipped with controlling devices embodying my invention. Fig. 2 is a similar view of the same with the parts in different positions. Fig. 3 is a vertical sectional view on an enlarged scale of the standard. Fig. 4 is a side elevation of the water cock and operating lever therefore. Fig. 5 is a plan view of the same. Fig. 6 is an elevation of the same as viewed from the opposite side from that as shown in Fig. 4.

10 is a water closet bowl of ordinary form, equipped with a seat 11 and cover 12, being connected therewith by means of the usual hinge device 13 at the rear.

14 is the water tank of usual form, connected with the bowl 10 by means of the discharge connection 15, and connected to the water supply system by means of the water supply pipe 16.

15 The tank 14 is provided with the usual controlling mechanism, including a ball cock, and which are operated by tripping mechanism and the tripping of which is effected by a downward pull on one arm of a lever 17. The operations effected by such pull on the lever 17 comprise opening the discharge from the tank to the bowl so as to effect the usual flushing thereof as desired; opening the water supply inlet to permit water to flow into the tank; closing the dis-

charge from the tank to the bowl, permitting the tank to fill; and finally closing the water supply to the tank when the latter is filled to the desired depth, and subject to the control of the ball cock. I provide an additional valve or cock 18 in the water supply pipe 16 and I provide means for simultaneously operating the said cock 18 and the lever 17. One method of doing this is shown in the drawing and the mechanism therefore comprises a controlling lever 19 which is connected to the cock 18 and also to the lever 17 and which is connected at its front end to a vertically reciprocating member 20, the upper end of which member 20 is maintained in contact with the lower side of the seat 11 by means of a spring 21. As shown the cock 18 has a T handle and the controlling lever 19 is connected to the arms of the same at its rear end by means of pins 22.

The connection between the controlling lever 19 and the tripping lever 17 consists of a cable or cord 23 which has one end connected to the lever 17 and the other end connected to the controlling lever 19 at some point as shown at 24 sufficiently remote from the water cock 18 to give the necessary movement, and intermediate to the said ends may pass over a guide pulley 25 that is preferably positioned to effect a substantially vertical pull on the tripping lever 17. The front end of the controlling lever 19 is pivotally connected to the reciprocating member 20 by means of a pin 26. The seat 11 overhangs the bowl 10 a little and the upper end of the reciprocating member 20 engages with the overhanging portion of the seat 11. The said upper end may be capped with a contact member 27. The reciprocating member 20 is part of a standard that is set up on the floor adjacent the bowl 10 suitably to engage with the seat 11 in the manner described and which comprises a fixed lower member 28, constituting the standard proper, suitable for slidably receiving the reciprocating member 20 and housing the spring 21. The lower member 28 is provided at the lower end with a supporting foot 29, in the form of a floor plate, and the body portion, above the floor plate 29, is tubular and a sliding fit internally for the reciprocating member 20. The spring 21 is housed in the lower part of the said body portion, between a plug 30 in the floor plate 29 and the lower end of the reciprocating

member 20. As shown the reciprocating member 20 is also tubular, and a washer 31 is interposed between the lower end thereof and the spring 21.

5 I prefer to use a self closing spring cock for the cock 18. The action of this spring is coöperative with that of the spring 21, and it is obvious that two springs are not necessary and that one spring of sufficient strength 10 can be used in lieu of two, and either of the two springs can be dispensed with. In the normal position, as shown in Fig. 1, the springs coöperate to hold the controlling lever 19 in the elevated position, which cor- 15 responds to the closed position of the cock 18, the seat 11 being tilted so as to be appreciably above the bowl 10, and the cable 23 is under tension, the tripping lever 17 being pulled downwardly to the lowermost position. 20 The result of this arrangement of the mechanism is that the discharge from the tank is open and the tank is normally empty and the water supply for the tank is shut off.

When the seat 11 is brought into use the same is lowered to the bowl 10 and the controlling lever 19 is brought to its lowermost position, as shown in Fig. 2. In this position of the mechanism the water supply cock 18 is in the open position and the cable 23 is slack, wherefore the tripping lever 17 is free to be raised to its uppermost position by the controlling mechanism in the tank and which latter permits the tank to be filled. Such filling will be properly effected, and substantially in an ordinary manner provided the seat 11 is maintained in the position for use for a sufficient length of time.

My mechanism as described dispenses with 40 the necessity of the push button 32 that is ordinarily used for operating the tripping lever 17, and which is positioned on the front of the tank and connected to the said tripping lever 17 by means of a rod 33, and 45 the same may be retained or not as desired.

It is understood that certain changes in details may be made to meet special conditions without avoiding the spirit and scope of my invention. For instance, in case of 50 having a floor of concrete, it may be preferred to support the standard by a bracket

from the wall, and other changes of a minor character may be made as mentioned.

It will be noted, as described, that where my invention is in use the water supply to 55 the water tank is turned on only when the seat is in use; that the bowl is automatically flushed immediately upon release of the seat; and that when the seat is not in use the water tank is empty. The result of this 60 combination is a saving of water by avoiding the waste that follows from leakage from the water tank to the bowl, which is a more or less common occurrence; by insuring a sanitary condition of the bowl; furthermore because the water tank is normally 65 empty, the danger of having the water therein freeze during cold weather is entirely obviated.

The means that I have devised to attain 70 the particular results mentioned are particularly adapted to use with modern openwork plumbing, in which the supply pipe 16 is in a vertical position, immediately at the rear of the bowl. This arrangement permits the 75 water supply cock 18 to be positioned in the said pipe 16 suitably to receive and support the rear end of the controlling lever 19. The said rear end of the controlling lever 19 is thus pivotally supported by the moving or 80 rotating member of the cock 18, being connected thereto by means of the pins 22.

I claim as my invention:—

In combination, a water closet bowl having a hinged seat, a tank having a tripping lever, a supply pipe connected to the said tank, a cock controlling the supply pipe, and a spring operated controlling lever having the body portion connected to the said tripping lever, and having one end connected to the said seat, the said cock being operatively connected to the other end of the said controlling lever and serving as a fulcrum support therefor, and the said supply pipe being in a vertical position adjacent the 90 said bowl, and serving as a support for the said cock and for the said other end of the lever connected thereto.

MARTIN J. KELLY.
